CLAIM

The ornamental design for an agricultural vehicle with a variable-height elevated platform, as shown and described.

DESCRIPTION

FIG. 1 is a perspective view of a first embodiment of an agricultural vehicle with a variable-height elevated platform in a lower height position.

FIG. 2 is a front elevation view of the agricultural vehicle with the variable-height elevated platform of FIG. 1.

FIG. 3 is a rear elevation view of the agricultural vehicle with the variable-height elevated platform of FIG. 1.

FIG. 4 is a left side elevation view of the agricultural vehicle with the variable-height elevated platform of FIG. 1.

FIG. 5 is a right side elevation view of the agricultural vehicle with the variable-height elevated platform of FIG. 1.

FIG. 6 is a top plan view of the agricultural vehicle with the variable-height elevated platform of FIG. 1.

FIG. 7 is a bottom plan view of the agricultural vehicle with the variable-height elevated platform of FIG. 1.

FIG. 8 is a perspective view of the agricultural vehicle with the variable-height elevated platform of FIG. 1 in an upper height position.

FIG. 9 is a front elevation view of the agricultural vehicle with the variable-height elevated platform of FIG. 8.

FIG. 10 is a rear elevation view of the agricultural vehicle with the variable-height elevated platform of FIG. 8.

FIG. 11 is a left side elevation view of the agricultural vehicle with the variable-height elevated platform of FIG. 8.

FIG. 12 is a right side elevation view of the agricultural vehicle with the variable-height elevated platform of FIG. 8.

FIG. 13 is a top plan view of the agricultural vehicle with the variable-height elevated platform of FIG. 8; and,

FIG. 14 is a bottom plan view of the agricultural vehicle with the variable-height elevated platform of FIG. 8.

(Continued)

The dot-dot-dash lines in the drawings are included for the purpose of illustrating portions of the agricultural vehicle with the variable-height elevated platform that form no part of the claimed design.
